VENETIAN BLIND

Tomlinson I. Moseley, San Francisco, Calif., assignor to Dalmo Sales Corporation, San Francisco, Calif., a corporation of California

Application December 16, 1935, Serial No. 54,531

5 Claims. (Cl. 156—17)

This invention relates generally to blinds of the type utilizing vertical spaced horizontal slats, which can be tilted at various angles, and which are commonly known as Venetian blinds.

5 It is an object of the invention to provide an improved operating mechanism for Venetian blinds, which will be characterized by smooth and convenient operation, simplicity of mechanical construction, compactness with respect to the 10 space occupied, and by the facility with which it can be installed.

It is a further object of the invention to provide an improved form of tilting mechanism which will be non-reversible, and which will dispense with the use of gears.

Further objects of the invention will appear from the following description in which the preferred embodiments of the invention have been set forth in detail, in conjunction with the accompanying drawings.

20 Referring to the drawings:

Fig. 1 is a cross sectional view looking down upon the operating mechanism as installed in a window, and taken along the line 1—1 of Fig. 2.

25 Fig. 2 is a side elevational view, in cross section, illustrating a blind incorporating the present invention, and taken along the line 2—2 of Fig. 1.

Fig. 3 is a cross sectional detail, taken along the line 3—3 of Fig. 1.

30 Fig. 4 is a cross sectional detail taken along the line 4—4 of Fig. 1.

Fig. 5 is a cross sectional detail taken along the line 5—5 of Fig. 1.

35 Fig. 6 is a cross sectional detail taken along the line 6—6 of Fig. 1.

As representative of a typical installation, the drawings illustrate my blind installed in conjunction with the frame 10 of a window. The working parts of the operative mechanism are carried by a box 11, which can be formed of suitable material such as sheet metal, and which includes a bottom wall 12 and side walls 13 and 14 (Figs. 4 to 6 inclusive). In order to removably support the box 11, suitable fittings 16 are shown attached to the upper corners of the window frame, and these fittings are formed to provide supporting shelves 17. Retaining clips 18 have forward inturned flanges 19, which overlap the edges of the wall 14, and which serve to retain the box 11 in proper position. These clips are releasably engaged with studs 20, carried by the fittings 16, whereby when the clips are detached, the box, together with operating parts carried by the same, can be removed.

55 The parts carried by the box 11 include a tu-

bular structure designated generally at 21, which is journaled for angular turning movement about a horizontal axis. This structure, which can be conveniently formed of sheet metal, consists of an intermediate metal tube 22 having its ends 5 fixed to the cylindrical drums 23. It will be noted that the tube 22 is of considerably smaller diameter than the drums 23, and that the drums together with the tube 22 are concentric with respect to a horizontal axis. Brackets 24 serve as 10 journals for the end portions of tube 22, and are in turn mounted upon the bottom wall 12 of the box 11.

Within the drum 23 are the pulleys 26, which are adapted to be engaged by the flexible pull-cords 27a and 27b. These pulleys are carried by stationary brackets 28, which in turn are mounted upon the bottom wall 12 of the box 11. In order to accommodate brackets 28, and in order that these brackets may not interfere with the 20 desired angular turning movements of the tubular structure 21, the peripheral walls of each drum 23, are cut away to provide the longitudinal slots 29, (Fig. 4), and segmental slots 31 (Figs. 2 and 4).

25 The horizontal slats 32 of the blind can be of conventional construction and formed of suitable material, such as wood. These slats are shown carried by two pairs of flexible straps 33, which extend downwardly from the drums 23. 30 The lower ends of the straps 33 are shown attached to a bottom bar 34, which has sufficient weight to straighten out the straps 33, when the pull-cords 27a and 27b are released. The individual support for each slat, with respect to 35 straps 33, can be formed by small cross strips 36 of suitable material such as fabric. The pull-cords 27a and 27b, after passing over pulleys 26, extend downwardly through openings 37 in the bottom wall 12, and through openings 38 in the 40 slats 32. The lower ends of these cords extend through openings 39 in the bar 34, and are attached thereto, as indicated at 41. The straps 33 engage opposite sides of the drums 23, and have their upper ends secured thereto, as indicated at 42. Therefore upon angular turning of the structure 21, the slats 32 together with the bottom bar 34, are tilted with respect to a horizontal plane.

45 A simple form of cam mechanism is provided 50 for turning the structure 21 to various angles. Thus, mounted upon the forward wall 14 of the box 11 (Fig. 5), there is a channel-shaped guide track 44, which extends horizontally and parallel to the axis of the structure 21. Slidably mounted

within the track 44, there is a rider 46. Mounted upon the outer surface of tube 22, there is a cam element 47, which is curved helicoidally as illustrated more clearly in Fig. 1. This cam element can be conveniently formed of a metal strip having its inner edge secured to the outer periphery of tube 22, and being twisted and curved helicoidally. Rider 46 is provided with a slot 49, in which the cam element 47 engages. It will be evident that upon sliding the rider 46 along its track 44, engagement with cam element 47 will cause the structure 21 to rotate upon its axis.

For convenient operation of the rider 46, cords 51a and 51b are provided. Cord 51a engages over a pulley 52, which in turn is carried by a mounting 53 adjacent one end of the box and near the front wall 14. From pulley 52, cord 51a extends back over the track 44, and engages another pulley 54, which is mounted near the other end of the box 11. Cord 51b extends over a pulley 56, near the pulley 54, and from the two pulleys 54 and 56, the cords extend downwardly to a convenient position for their operation.

The two pull-cords 27a and 27b extend from one end of the structure 21, and engage over a pair of pulleys 57. From these pulleys the cords extend downwardly through an opening 58 in the bottom wall 12 (Fig. 6), to a convenient position for their operation. The lower ends of the cords 27a and 27b, and likewise the lower ends of cords 51a and 51b, may be connected together. Pulleys 57 are shown carried by a suitable fixed mounting 59, which can be provided with a suitable cord gripping latch 61. This latch may be of conventional construction, and need not be described in detail. In general it serves to frictionally engage the cords 27a and 27b, when the blind is raised, whereby the blind is retained in a desired raised position. Disengagement of the latch is effected by a slight pull upon the cords 27a and 27b, accompanied by lateral swinging of the hanging cord portions from normal vertical position.

Operation of the blind described above can be briefly reviewed as follows:—Assuming that the straps 33 are partially or completely extended, the slats 32 can be tilted to any desired angle, by pulling upon the cords 51a and 51b. Manipulation of these cords causes sliding movement of the rider 46, which by virtue of its engagement with the cam element 47, causes angular movement of the tubular structure 21. If it is desired to raise or lower the blind, this can be accomplished by manipulation of the cords 27a and 27b.

Desirable characteristics of my blind are as follows:—The operation mechanism is relatively simple and compact, and a minimum amount of labor is involved in installing the blind for a particular window. Smooth and positive operation is secured at all times. The cam means which is utilized in effecting angular rotation of the structure 21, is non-reversible, in that torque exerted upon the structure 21, will not cause sliding movement of the rider 46. At the same time angular movement is transmitted to the structure 21 by sliding of the rider 46, in a positive manner, without the use of gears, and without the use of a driving pulley over which a looped cord must operate.

I claim:

1. In a blind of the Venetian type wherein slats are adapted to be tilted and to be raised and lowered by pull-cords, an elongated tubular struc-

ture, means for supporting said structure in a horizontal position for angular movement about its axis, pull-cords disposed within said structure, and means for effecting angular movement of said structure in opposite directions, said means including a rider, means serving to carry the rider for sliding movement in the direction of said axis, and a cam element acting between the rider and said structure. 5

2. In a blind of the Venetian type wherein slats are adapted to be tilted and to be raised and lowered by pull-cords, an elongated tubular structure, said structure comprising a pair of substantially cylindrical end drums together with a tube connecting said end drums, the tube having a smaller diameter than said drums and being concentric with respect to the same, means for supporting said structure in a horizontal position for angular movement about its axis, pull-cords disposed within said structure and extending to the exterior through one end thereof, and means for turning said structure in opposite directions, said means including a rider, means serving to carry the rider for sliding movement in the direction of said axis, and a cam element 10 15 20 25 30 35 40 45 50 55 60 65 70 75 80 85 90 95 100

3. In a blind of the Venetian type wherein slats are adapted to be tilted and to be raised and lowered by pull-cords, an elongated tubular structure, said structure comprising a pair of substantially cylindrical end drums and a tube connecting the end drums, the tube having a smaller diameter than the drums and being concentric with respect to the same, means for supporting said structure in a horizontal position for angular turning movement about its axis, pull-cords disposed within said structure and extending to the exterior from one end of the same, and means for effecting angular turning movements of said structure in opposite directions, said means including a rider, a track serving to carry the rider for sliding movement in the direction of said axis, and a curved cam element mounted upon the outer periphery of said tube and operatively engaged by said rider, said element extending between 45 50 55 60 65 70 75 80 85 90 95 100

4. In a blind of the Venetian type wherein slats are adapted to be tilted and to be raised and lowered by pull-cords, an elongated tubular structure, said structure comprising a pair of substantially cylindrical end drums together with a tube connecting the end drums, the tube having a smaller diameter than the drums and being concentric with respect to the same, means for supporting said structure in a horizontal position for turning movements about its axis, pull-cords disposed within said structure and extending to the interior through one end thereof, pulleys mounted within said drums over which said cords operate, fixed mounting for said pulleys extending to the exterior of said drums, said drums having openings in their side walls to accommodate said mountings, a pair of flexible slat supporting members depending from each of said drum portions, said elements engaging the outer peripheries of said drums and being secured to the same, and means for turning said structure about its axis in opposite directions, said last means including a rider, track means serving to carry the rider adjacent one side of said tube for sliding movements in the direction of said axis, and a curved cam element carried by the outer periphery of said tube and engaged by said rider, said cam element extending between said drums. 65 70 75 80 85 90 95 100

5. In a blind of the Venetian type wherein slats 75

are adapted to be tilted and to be raised and lowered, an elongated tubular structure, said structure comprising a pair of substantially cylindrical end drums together with a tube connecting 5 the end drums, the tube having a smaller diameter than the drums and being concentric with respect to the same, means for supporting said structure in a horizontal position for angular movements about its axis in opposite directions, 10 pull-cords disposed within said structure and extending to the exterior from one end of the same, pulleys mounted within said end drums and engaged by said pull-cords, fixed mountings for said pulleys extending to the exterior of said drums, said drums having openings to accommodate said mountings, flexible slat supporting members depending from said drums, the upper 5 end portions of said members engaging the outer peripheries of said drums and being secured to the same, and means enabling rotation of said structure in opposite directions, to effect tilting the slats carried by said flexible members. 10
